UNITED STATES PATENT OFFICE.

WILLIS WALTER LINDER, OF CHARLOTTE, NORTH CAROLINA.

BALANCING-MACHINE.

1,069,272.

Specification of Letters Patent.

Patented Aug. 5, 1913.

Application filed July 17, 1912. Serial No. 710,049.

To all whom it may concern:

Be it known that I, WILLIS WALTER LINDER, a citizen of the United States, residing at Charlotte, in the county of Mecklenburg and State of North Carolina, have invented certain new and useful Improvements in Balancing-Machines, of which the following is a specification, reference being had to the accompanying drawings.

This invention relates to new and useful improvements in balancing machines and more particularly to a balancing or testing machine for fliers used in connection with roving frames and my object is to provide a device which will readily indicate when the flier with the presser thereon is not true.

A further object of the invention resides in providing a spindle for carrying the flier and an oscillating or vibrating member in connection with the spindle which latter member is only adapted to vibrate when the flier is unbalanced and a still further object resides in providing a device which is extremely simple and durable in construction, inexpensive to manufacture and one which will be very efficient and useful in operation.

With these and other objects in view, the invention consists in the novel features of construction, combination and arrangement of parts as will be hereinafter referred to and more particularly pointed out in the specification and claims.

In the accompanying drawing forming a part of this application, Figure 1 is a side elevation of the device. Fig. 2 is a top plan view thereof. Fig. 3 is a vertical transverse section through the same as seen on line 3—3, Fig. 2. Fig. 4 is a longitudinal section as seen on line 4—4, Fig. 2.

In describing my invention, I shall refer to the drawings in which similar reference characters designate corresponding parts throughout the several views and in which—1 indicates a base or platform upon one end of which is mounted the supporting standards or the like 2, having bearings formed at the upper ends thereof, said bearings rotatably receiving therein an axle or shaft carrying the grooved drive wheel 3, and a crank 4 carried on the one end of the shaft or axle forms a means whereby the wheel may be readily rotated in the bearings.

Mounted on the opposite end of the base or platform 1 is a supporting frame 5 on the upper portion of which is carried the top

plate or table 6 and loosely disposed through this plate or table is a spindle 7, the lower end of which is rotatably supported on a stud or the like 8 mounted on the base 1. This spindle extending vertically through the top plate 6, has a pulley 9 mounted thereon, adjacent its lower end, with which is engaged a guide belt or the like 10, the latter also extending over the drive wheel 3, above referred to. This spindle is adapted to receive on the upper end thereof, a flier 11 carrying the presser 12, such as is used on cotton spinning machines and it will be appreciated that as this spindle 7 is caused to rotate through the manual rotation of the drive wheel, said flier and presser will also be rotated therewith.

My invention primarily contemplates a means to determine the trueness of the flier, that is, whether or not the same is properly balanced and to this end, the top plate or table 6 is provided with a peculiarly shaped groove or opening 13 extending for a considerable portion of the length thereof and leading to a cross bar 14 mounted on the rear end of the table or top plate. This groove or opening 13 tapers outwardly toward its outer end, the same receiving therethrough the spindle 7 and removably secured to the bar 14, on said top plate, is a forwardly projecting block or the like 15, which is designed somewhat similar to the groove or opening 13. This projecting block or the like 15 extends for a portion of the length of said groove 13, and pivotally secured to the outer end thereof through the medium of a vertically extending pintle 16, are the upper and lower projecting arms 17 formed on a vibrating block 18. This vibrating block 18 is substantially circular in plan and receives therethrough the spindle 7 and in order to keep the same disposed in proper position, the leaf springs 19 are secured to the side faces of the block 18 and projected forwardly to loosely contact with the periphery of the block 18 at diametrically opposite points thereon.

Pivotal and loosely engaged with the block 18 forward of the spindle 7 is an indicating needle or the like 20, said needle being fulcrumed intermediate of its ends on a stud 21 mounted vertically on the top plate 6. Said needle is bent somewhat downwardly and offset from the fulcrum point so as to dispose the outer or free end thereof in close proximity to said top plate 6 and the

outer end of the top plate 6 which is convexed at its free edge, is provided with a scale 22 which is adapted to coöperate with the needle 20.

- 5 In operation, when the spindle 7 is rotated, the flier with the presser thereon will also be rotated and if the flier is not perfectly balanced, the block 18 will be caused to vibrate, thereby vibrating the needle 20.
- 10 The unbalancing of the flier may be caused by the fact that the one arm thereof may be bent or the presser is too heavy or too light, and in any instance, it can be determined by the indicating needle and scale.
- 15 From the foregoing, it will be seen that I have provided a device which is extremely simple and durable in construction, inexpensive to manufacture and one which will be very efficient and useful in operation.
- 20 While I have particularly described the elements best adapted to perform the functions set forth, it is obvious that various changes in form, proportion and in the minor details of construction may be resorted to without departing from the spirit or sacrificing any of the principles of the invention.

Having thus described this invention, what I claim is:—

1. A balancing machine of the class described comprising a support, a spindle extending vertically therethrough, a member pivotally mounted on said support and co-operating with said spindle to vibrate upon the rotation of the latter, means to yieldingly retain said pivotal member in position on the support, an indicating needle fulcrumed on said support and having piv-

tal connection with said pivotal member, a scale mounted on the support to coöperate with said needle, and means to rotate said spindle.

2. A balancing machine of the class described comprising a support, a spindle extending vertically therethrough, a member pivotally mounted on said support adapted to coöperate with said spindle, spring members engaged with said pivoted member to normally retain the same in position, an indicating needle fulcrumed on said support and having pivotal connection with said pivoted member, a scale formed on said support to coöperate with said needle, and means to rotate said spindle.

3. In a balancing machine of the class described, the combination with a table and support therefor; of a rotating spindle extending vertically through said table, a projection mounted on said table, a block pivotally mounted on said projection and loosely receiving said spindle therethrough, spring members carried on said projection and loosely contacting with said block to normally dispose the same in position, an indicating needle fulcrumed on said support and having pivotal connection with said block, a scale formed on said table to coöperate with said needle; and means to rotate said spindle.

In testimony whereof I hereunto affix my signature in the presence of two witnesses. 70

WILLIS WALTER LINDER.
